UNITED STATES PATENT OFFICE

JOSEPH SLADDIN, OF LAWRENCE, MASSACHUSETTS, ASSIGNOR TO HIMSELF
AND JOHN LORD, OF SAME PLACE.

IMPROVEMENT IN MACHINES FOR MAKING HARNESS FOR LOOMS.

Specification forming part of Letters Patent No. 80,774, dated August 4, 1868.

To all whom it may concern:

Be it known that I, JOSEPH SLADDIN, of Lawrence, in the county of Essex and State of Massachusetts, have invented a new and useful Improvement in Machinery for Making Loom-Harness; and I do hereby declare that the following is a full, clear, and exact description thereof, which will enable those skilled in the art to make and use the same, reference being had to the accompanying drawings forming part of this specification.

My invention relates to certain improvements in machinery for weaving loom-harness, whereby, by an automatically-operating machine, I am enabled to form the heddle-eyes and at the same time secure the yarn to the rig-bands in a firm and substantial manner; and it consists in the arrangement of the different parts of the machine for accomplishing the same, as will be more particularly described by reference to the drawings accompanying this specification, in which—

Figure 1 represents a plan view of my improved machine; Fig. 2, a side elevation of the same; Fig. 3, a section on the line $x-x$ of Fig. 1, and Fig. 4 represents a cross-section on the line $y-y$, Fig. 1. Fig. 5 represents view of the end of the needle a ; Fig. 6, a perspective view of the twisting-fingers e ; Fig. 7, a view of the push-fingers f ; Fig. 8, a view of the twister d ; Fig. 9, a view of a portion of the rig-band, showing the manner of securing the heddles to it, and Fig. 10 a view of a portion of the heddles.

Similar letters represent corresponding parts in all the figures.

A represents the frame of the machine, and B the driving-shaft, which receives motion from any competent prime mover, and which communicates motion to all the other moving parts. a is a stationary needle rigidly secured to an extension, A' , of the frame of the machine, and is provided on its upper side with a wide and deep groove nearly its whole length, and at its operating end with two eyes, one on each side. a^1 represents a pair of fingers projecting downward, so as to pass one on each side of the needle. They are suspended from the two swinging arms a^2

a^3 , connected to the oscillating shafts a^4 a^5 , respectively, which receive motion from cams a^6 a^7 on the shaft C , through the medium of arms a^8 a^9 on the said shafts a^4 a^5 . A right-angled vertical extension of the arm a^2 carries at its upper end guide-eyes for conducting the yarn from the bobbins to the needle.

b^1 b^1 represent a pair of fingers having right-angled extensions at their lower extremities, serving the purpose of wipers, which are acted upon by the pins b^2 b^2 on the hooker-arms c c , to force the said fingers up to the needle, which is provided with grooves or recesses on each side to receive them. The said fingers are actuated in the opposite direction by springs b^3 b^3 acting upon arms b^4 b^4 secured to the axial pivots b^5 b^5 , to which the said fingers are also secured, and which have a bearing in a vertical support suspended from one of the cross-ties of the frame. c c represent a pair of hooker-levers, which terminate at their upper ends, each in a pair of hooks, c^1 c^1 . The said hooker-arms are supported at their lower ends on the levers c^3 c^3 , which are pivoted to the frame at c^4 c^4 , the opposite ends of said levers being connected to and actuated by connecting-rods c^5 c^5 . The rods at their upper ends are connected to the levers c^6 c^6 , which are pivoted to the frame at c^7 c^7 , and carry friction-bowls, which are actuated by cams c^8 c^9 on the shafts c^9 c^9 . These shafts are actuated from the shaft D through the mediation of bevel-wheels. The said shaft D is actuated by the driving-shaft B through the wheels B' B' . The said hooker-arms have another movement communicated to them by cranks c^{10} c^{10} , and connecting-rods c^{11} on the shafts c^9 . d represents a twister on the end of shaft d' , arranged in the plane of the needle and at right angles to the same, and has an oscillating motion communicated to it through the mediation of the pinion d^2 , wheel d^3 , pinion d^4 , rack d^5 , and cam d^6 on the shaft C . The return motion is effected by the action of the spiral spring a^7 on the rack-bar d^5 after the cam-tappet d^6 has passed out of action with the friction-bowl on the said rack-bar. d^9 is a friction-wheel, which serves to bear the rack-bar up to the proper connection with the

pinion d^4 . E represents a pair of fingers on the top of a vertical shaft, e^1 , which is made to oscillate through a quarter of a revolution by means of the crank e^2 and slide e^3 , which are actuated by cam e^4 on the shaft D, to throw the said fingers around, so as to stand in line with the axis of the twister d . The return movement is given by the spring e^5 . f represents a pair of sliding fingers arranged in line with the needle, and connected to the slide f^1 , which is moved forward by a cam on the shaft D, which works against the vibrating lever f^2 , which is connected to the slide f^1 at its upper end. The return movement of the said slide and fingers is effected by the recoil of the spiral spring f^3 .

g g represent hooks to receive the thread from the carrying-hooks c^1 c^1 . They receive motion from cams on the lapper-cylinders h h through the action of the levers g^1 g^1 and oscillating shafts g^2 g^2 . h h are cylinders through which the rig-bands pass, and which are carried in brackets h^1 h^1 . They are actuated by the wheels h^2 h^2 , from the shafts c^6 , through intermediate wheels h^3 . These lapper-cylinders carry at one end the lapper-bobbins and at the other a guide-eye, through which the yarn is carried from the lapper-bobbins. i i are barbed knitting-needles of the ordinary construction, secured to the reciprocating cross-head i^1 , which is actuated in one direction by a cam on the shaft C, through the arms i^2 i^3 on the rock-shaft i^4 , and in the opposite direction by a spring, i^5 . j j are horizontal guide-supports for the needles, through an opening in which, near their inner ends, the said needles work. The part j^1 serves as a "knocker over," to knock off the stitches from the said needles. j^2 j^2 are spring-pressers for pressing the barbs down into the grooves in the needle when it is required to slip the loop off the said needles. j^3 j^3 are presser-rollers for holding the rig-bands up against the ends of the needle-supports. They are secured to the brackets h^1 h^1 by adjustable connections. k k are spring-arms secured to the extension A¹ at k^2 k^2 . Their inner ends extend inward to about the weaving-line, or the line of movement of the hookers c^1 c^1 , and their office is to receive upon their upper surface the web as it is woven and passes out of the machine. Their inner ends are, at the proper time, raised by the vertically-sliding rods k^3 k^3 , actuated by cams on the shaft C, to prevent the web being obstructed by catching upon any of the parts of the machine as it moves along. l is a presser-pad actuated by the shaft a^6 , and is for the purpose of holding the web down against any tendency of the fingers a^1 to raise it up. m is a horizontally-sliding carriage, from which project two vertical pins, to which the rig-bands are secured. This carriage is caused to slide back and forth on the guide-rods m^1 m^1 by means of the screw m^2 , shown in dotted lines in Fig. 1, gear-wheels m^3 , also shown in dotted lines, and shaft m^4 , which receives its motion

from a train of wheels on one side of the machine connecting with the main wheel on the driving-shaft, as clearly shown in the same figure.

The operation of my improved machine is as follows: The carriage m being moved up to a position near the frame A, the cords which form the rig-bands are drawn off the bobbins n n over the guide-pulleys n' n' through the lapper-cylinders h , and fastened to the vertical pins in the carriage m, the weights o o, suspended from the bobbins n , keeping the said cords under the proper tension. The yarn for forming the heddles is drawn from the yarn-bobbins p p through the tension-rings p^1 and guide-eyes p^2 p^2 and p^3 p^3 over the pulleys p^4 , thence through the groove in the upper face of the needles to the eyes, one of which is passed through each eye; thence to the rig-band, where they are fastened. The yarn from the lapping-bobbins q q is then drawn through the lapper-cylinders and the guide-eyes, and fastened to the same place. The twister d now seizes hold of the yarn on one side of the needle a, and carries it downward around the fingers e, which have been previously turned so as to point in the direction of the said twister. The fingers e then turn back so as to point toward the needle a, when the push-fingers f move forward and push the loop off from the fingers onto the needle. The fingers a^1 now move down onto the loop and hold it while the fingers b^1 rise up between the yarn and the needle, and, moving outwardly, carry loops a sufficient distance for the hookers c^1 c^1 to take them from the fingers and carry them to the spoon-shaped fingers g, which rise up and take the said loops from the hookers, and hold them, so that the barbed needles can take hold of them. At the same time the yarn from the lapper-cylinders laps around the barbed needles and is wound around the rig-bands, when the hooks g drop away from the yarn, and the needles are moved back and closed against the pressers j, in the usual manner of knitting.

The operation is then repeated, and as each operation, as thus described, is performed, the carriage m is moved outwardly a distance corresponding with the space due to one heddle-yarn, or sufficiently to take up the slack and keep a proper tension on the yarn; or, a take-up apparatus similar to that employed in ordinary looms, may be used.

I claim as new, and desire to secure by Letters Patent—

1. The combination, with the twister d, of the means, substantially as described, for operating the same, as and for the purpose specified.

2. The combination of the spoon-hookers g with the hooker-fingers c^1 c^1 and the needles i i, substantially as and for the purpose described.

3. The combination of the lapper-cylinders,

having guide-eyes, as described, with the spoon-shaped hook g and needles i , substantially as and for the purpose described.

4. The combination, with the needle guide and support j , of the presser-wheels j^3 , when arranged and operating as and for the purpose specified.

5. The combination, with the device for forming the loops, substantially as described, of the devices for knitting the heddles onto

the rig-bands, substantially as and for the purpose described.

6. The combination, with the knitting device herein described, of the lifting guide-bars k , as and for the purpose described.

JOSEPH SLADDIN.
